United States Patent Office.

GEORGE KUHLMANN, OF NEW YORK, N. Y.

Letters Patent No. 72,646, dated December 24, 1867; antedated December 12, 1867.

IMPROVED TABLE.

The Schedule referred to in these Letters Patent and making part of the same.

TO ALL WHOM IT MAY CONCERN:

Be it known that I, GEORGE KUHLMANN, of the city, county, and State of New York, have invented a new and useful Improvement in Tables; and I do hereby declare that the following is a full, clear, and exact description of the construction and operation of the same, reference being had to the annexed drawing, making a part of this specification, in which—

Figure 1 is an end view of the table as it appears when closed.

Figures 2 and 3 are, respectively, end and side views when the leaves are extended.

Figure 4 is an enlarged horizontal view of the spring-catches $\alpha\alpha$, &c., shown in figs. 2 and 3.

Construction.

The centre leaf b is supported by the ends $c c$, which are hollow panel-work, and are themselves secured to the feet $d d$, &c., and are longitudinally braced by the cross-piece e , connecting them, the whole being made of any suitable wood, and of any desirable design. The lower leaf, f , has openings made in it of the proper shape, and sufficient distance apart to allow it to slide freely up and down on the end pieces $c c$, and is supported and moved by the cords $g g$, &c., which pass over the pulleys $h h$, &c., and are secured to the end pieces $i i$, which are the supports for the upper leaf. The centre leaf is made thicker than the others, to accommodate the spring-catches $\alpha\alpha$, which are made of brass or other suitable metal, and are shown, on a large scale, in fig. 4.

Operation.

To extend the table, elevate the leaf k with the hand, and the cords will pass over the pulleys and allow the leaf f to descend. When the leaf k has been elevated to a certain point, the catches $\alpha\alpha$ will enter the recesses, made in the sides $i i$, to receive them, and thereby arrest the motion, and sustain any desirable weight.

To close the table, place the finger in recess m , as shown in fig. 2, and pull. The effect will be, the catches $\alpha\alpha$ will be removed from the recesses, and the weight of the leaf k will cause it to descend, and, at the same time, by the action of the cords over the pulleys, elevate the leaf f , until both resume the position shown in fig. 1.

Claim.

What I claim as my invention, and desire, by Letters Patent, to secure, is—

The application, to tables, of the arrangement of the cords $g g$, &c., pulleys $h h$, &c., and spring-catches, shown by fig. 4, all used for extending vertically, and supporting, when extended, the leaves f and k , as herein-before described.

GEORGE KUHLMANN.
